[57] CLAIM

The ornamental design for a snow plow light, as shown and described.

DESCRIPTION

FIG. 1 is a perspective view of a snow plow light embodying my new design;

FIG. 2 is a front elevational view thereof on an enlarged scale;

FIG. 3 is a top plan view thereof on an enlarged scale;

FIG. 4 is a rear elevational view thereof on an enlarged scale;

FIG. 5 is a bottom plan view thereof on an enlarged scale;

FIG. 6 is a right side elevational view thereof, the left side being similar except for the orientation of the mounting elements on the bottom surface.

FIG. 1

FIG. 3

FIG. 2

FIG. 4

FIG. 5

FIG. 6
